UNITED STATES PATENT OFFICE.

WALTER C. BRANDT AND JESSE A. LEWIS, OF ST. PAUL, MINNESOTA.

KEY FASTENER.

1,410,527.

Specification of Letters Patent. Patented Mar. 21, 1922.

Application filed February 7, 1920. Serial No. 357,046.

To all whom it may concern:

Be it known that we, WALTER C. BRANDT and JESSE A. LEWIS, citizens of the United States, residing at St. Paul, in the county of 5 Ramsey and State of Minnesota, have invented a new and useful Improvement in Key Fasteners, of which the following is a specification.

Our invention relates to a key fastener 10 which is particularly adapted to operate in connection with the door lock to hold the key in place to operate the lock and against being forced out of the same by a burglar or anyone trying to open the lock from the 15 outside of the door.

A further object of our invention is in a key fastener which is attached to the door or lock by a flexible means to hold it against disengagement therefrom in a simple manner.

It is also an object of our invention to provide a fastener which when inserted in the key slot in the plate or escutcheon of the lock will move by gravity into locking or 25 fastening position to prevent removal of the key from the lock and also to provide a key fastening means which is easily and readily removable from the lock key slot so that when it is desired the key can be removed 30 from the door lock.

Other features and advantages of our fastener will be clearly set forth in the specification and claims.

In the drawings forming part of this 35 specification:

Figure 1 is a perspective view of an ordinary lock in place in a door, only a portion of the door being illustrated, and showing our fastener attached thereto.

40 Figure 2 is a cross sectional elevation of the door and lock, illustrating our fastener in operating position.

Figure 3 is a perspective view of a portion of our fastener.

45 Figure 4 is a geometrical development of a stamping of a different form of fastening device.

Figure 5 is a perspective view of the form 50 illustrated in Figure 4 of the fastener as it would appear when bent in shape ready for use.

In the drawings A represents a portion of a door in which an ordinary lock B is secured in the usual manner and which is provided with a plate or escutcheon 10, having 55 a key slot 11 through which the key 12 is inserted into the lock to operate the same.

When the key 12 is in position to operate the key bolt 13 of the lock B it is very desirable in many instances to hold the key in 60 operating position against removal by accident or otherwise and to accomplish this we have designed our fastener C. The fastener C is composed of the plate 14, to which is attached the key engaging or locking lug 65 15 by the shank 16 to rigidly hold the lug 15.

The member 15 is attached near one end of the plate 14 to form a weighted portion 17 at the opposite end to the fastening of the shank 16 on the plate 14, which serves to 70 cause the lug 15 to extend horizontally in the key slot of the lock with the shoulders 18 formed adjacent the shank 16 in position to engage the inner surface at each side of the slot 11 in the escutcheon of the lock to 75 prevent the lug 15 from disengagement with the escutcheon. The lug 15 is formed with an offset end 19, which serves to engage the operating head or flange 20 of the key 12 to hold it against disengagement from the 80 lock, while the weighted end 17 will cause the fastener to automatically move into locking position by gravity after the lug 15 is inserted through the slot 11.

The offset end 19 prevents tampering with 85 the lug 15 and to cause any tool which may be used from the outside of the door to try and pick or engage the locking lug 15 so as to force the fastener C out of the key slot 11. The wide, flat nature of the lug 15 has a 90 tendency to insure the lug engaging the key flange 20 and allow the lug to rest against the lower portion 21 of the key slot.

The weighted end 17 of the fastener C is formed with a hole 22 in which a flexible 95 member 23, such as a chain or other suitable flexible means, engages to connect the fastener C with the door A or the escutcheon of the lock by one of the screws 24. In this manner the fastener C is connected with the 100 lock and door against disengagement therefrom but which allows the key lug 15 to be

withdrawn from the key slot 11 by raising and partially rotating the same and after the fastener is removed from the key slot the key can be removed from the lock in the ordinary manner. When the fastener C is not desired for use it can hang from the chain or flexible member 23. The flexible member or chain 23 acts to increase the action of the weighted end 17 of the fastener 10 C to cause it to turn by gravity automatically into locking position when the lug 15 is inserted in the key slot.

The key fastening element of our device may be formed of a single piece of material 15 to form a key fastening element, such as D, illustrated in Figures 4 and 5. Figure 4 illustrates the fastener D in its geometrical development as it would appear stamped from a thin, flat sheet of material, while 20 Figure 5 illustrates the finished article bent into the proper shape. In this construction the key engaging lug 15' is similar in shape and appearance to the lug 15, while the shank 16' connects the lug 15' with the 25 weighted and enlarged end 17'. The weighted end 17' is formed with a hole 22' in which one end of the chain 23 engages to connect the fastener D to the escutcheon of the lock by the screw 24 in the same manner 30 as illustrated in Figure 1.

The key fastening or enlarging element illustrated in either of the constructions described performs the same function and is primarily adapted to turn automatically in- 35 to locking position in the key slot due to the weighted ends 17 and 17', which is urged by the additional weight of the chain or flexible member 23. This feature makes the device practical for general use and prevents 40 any possibility of the device not being in position to operate as a key fastener. The fasteners C or D do not interfere with the ordinary operation and functions of the key 12 and will prevent the key from being dis- 45 engaged from the lock, thus serving a practical purpose for holding the key in the lock and door during the movement of the door in ordinary use. The simple, inexpensive construction of our device adds to its merits 50 and practical features.

In accordance with the patent statutes we have described the principles of operation of our invention, together with the apparatus which we now consider to represent the best 55 embodiment thereof, but we desire to have it understood that the construction shown is only illustrative and that the invention can be carried out by other means and applied to uses other than those above set forth 60 within the scope of the following claims:

1. In combination with an escutcheon, a key hole in the same, a key fastener having an elongated member insertable through said key hole and a portion rotatable within

the key hole and a weight for rotating said 65 rotatable member within the key hole to cause said elongated member to extend across said escutcheon on the inner side of the key hole.

2. A device for holding a key in a lock, in- 70 cluding a key engaging member, an offset portion connected to said member to cause the same to turn automatically into locking position and means for attaching said member to the lock or door.

3. A device for holding a key in a lock, comprising a member adapted to engage the key and offset means formed on said member to cause said member to be rotated into operating position in the escutcheon of a 80 lock to hold a key against disengagement from a lock.

4. A key engager adapted to hold a key in a lock, comprising a plate, an engaging lug secured to said plate, a weight to automatically move said lug into latching position when inserted in the key slot of the lock through the lock plate secured to the door and means for latching said lug against disengagement from said plate.

5. A key fastener in combination with a lock, an escutcheon, an engaging lug, escutcheon engaging shoulders formed on said lug, a weight or offset member adapted to turn said lug into key holding position 95 and a flexible member adapted to connect said lug and weight member to said escutcheon and lock.

6. A key fastener in combination with a lock, a key engaging lug formed on one end 100 of said member, a weighted portion formed on the other end of said member, a thin shank connecting said lug and weight portions of said fastener, a shoulder formed on the back of said key lug adapted to hold said 105 lug in engaging position to hold a key in a lock and a flexible member adapted to hold a key fastener connected to a lock and door to allow it to be used to hold a key or remove it from the lock and adapted to hang 110 in readiness for use when desired.

7. A key fastener, including a key en- 115 gaging lug, a weighted end, a flexible mem- ber adapted to hold said fastener to prevent displacement of the same, said weighted end and flexible member forming weight means to cause said key lug to be automatically moved into operative position when the same is inserted in the key slot.

8. A key retainer comprising a neck, a 120 head mounted on said neck on one end there- of and a weight secured to said neck at its other end.

9. A key retainer comprising a neck, a 125 head mounted on one end of said neck and a weighted member mounted on said neck in offset relation to said head.

10. A key retainer comprising a neck, a

head mounted on said neck having a pair of shoulders formed thereon and a body portion secured to the other end of said neck.

11. A key retainer comprising a head of a width greater than the thickness thereof, a neck having a width substantially equal to the thickness of said head and a body member secured to said neck.

12. A neck retainer comprising a horizontally positioned key, a head issuing horizontally outward from said neck having an upwardly turned end and a depending body portion secured to the other end of said neck. 10
